US00D968711S

(12) **United States Design Patent** (10) **Patent No.:** **US D968,711 S**
(45) **Date of Patent:** ** *Nov. 1, 2022

(54) **LIP PRODUCT CONTAINER**

(71) Applicant: **EOS PRODUCTS, LLC**, New York, NY (US)

(72) Inventors: **Jonathan Teller**, New York, NY (US); **Sanjiv Mehra**, New York, NY (US); **Peter Waxman**, New York, NY (US); **Joseph Speter**, New York, NY (US); **Karim Rashid**, New York, NY (US); **Bart Ruijpers**, New York, NY (US); **Olivia Blechschmidt**, New York, NY (US)

(73) Assignee: **EOS PRODUCTS, LLC**, New York, NY (US)

(*) Notice: This patent is subject to a terminal disclaimer.

(**) Term: **15 Years**

(21) Appl. No.: **29/659,339**

(22) Filed: **Aug. 8, 2018**

(57) **CLAIM**

The ornamental design for a lip product container, as shown and described.

DESCRIPTION

FIG. 1 is a perspective view of a lip product container in an open configuration showing my design; FIG. 2 is a front elevational view of the lip product container of FIG. 1; FIG. 3 is a rear elevational view of the lip product container of FIG. 1; FIG. 4 is a left side elevational view of the lip product container of FIG. 1; FIG. 5 is a right side elevational view of the lip product container of FIG. 1; FIG. 6 is a top plan view of the lip product container of FIG. 1; and, FIG. 7 is a bottom plan view of the lip product container of FIG. 1. The broken lines illustrate portions of the lip product container that form no part of the claimed design.

1 Claim, 7 Drawing Sheets
